UNITED STATES PATENT OFFICE.

SAMUEL I. FLOURNOY, OF KANSAS CITY, MISSOURI, ASSIGNOR, BY MESNE ASSIGNMENTS, TO W. S. DICKEY CLAY MANUFACTURING COMPANY, OF KANSAS CITY, MISSOURI, A CORPORATION OF DELAWARE.

CLAY-PIPE-FORMING PRESS.

Application filed April 9, 1925. Serial No. 21,940.

To all whom it may concern:

Be it known that I, SAMUEL I. FLOURNOY, a citizen of the United States, residing at Kansas City, in the county of Jackson and 5 State of Missouri, have invented certain new and useful Improvements in Clay-Pipe-Forming Presses; and I do declare the following to be a full, clear, and exact description of the invention, such as will enable 10 others skilled in the art to which it appertains to make and use the same, reference being had to the accompanying drawings, and to the figures of reference marked thereon, which form a part of this 15 application.

This invention relates to clay pipe forming presses, and the primary object of the invention is to provide a geared mechanism for operating the clay plunger or follower 20 of the press so that the stroke of the plunger will be positive.

Ordinarily the plunger is operated by steam or air. The clay offers considerable resistance to the plunger, and since both 25 steam and air are compressible fluids, it is impossible at all times to obtain a positive uniform stroke of the plunger. Prior to my invention it has been recognized that it is desirable to provide a plunger with some 30 sort of geared mechanism so that a positive action could be imparted to the plunger, but in so far as I am aware, no one prior to my invention has successfully solved the problem.

With my invention the same uniform pressure will be exerted against the clay in the pipe-forming cylinder throughout the entire stroke of the piston. The novel manner in which I accomplish the desired re- 35 sults will be apparent by reference to the following description in connection with the accompanying drawings in which—

Fig. 1 is a side elevational view of the plunger operating mechanism and the 40 plunger, part of the pipe-forming cylinder being shown in section, and

Fig. 2 is an edge view of the mechanism.

Referring now to the drawings by numerals of reference, 1 and 2 designate two 45 brackets or standards, preferably cast integral with the base 3. Each bracket is substantially a counterpart of the other. Each consists of a central web portion 4, and an up-standing bar 5 at one end, with a

similar bar 6 at the other. Each bracket 55 is provided with four elongated bearing slots 7, 8, 9 and 10 to receive bearing blocks 11, 12, 13 and 14 respectively. Each block is adapted to be moved in a horizontal plane and held in an adjusted position by opposing set screws 15 and 16, and at the edges of each slot is a bridge piece 17 with a set screw 18 in it to adjust each one of the shafts 19 longitudinally. There are four shafts between the two complementary 60 corners of the brackets. Each shaft 19 carries a roller 20 with a flange 21 to engage in a longitudinal groove in the plunger bar 22. The plunger bar 22 has two grooves 65 23 and 24 in its respective edges engaged by the flanges 21 of the roller 20. The plunger bar is mounted between the brackets and between the flanges of the rollers, there being two rollers on each edge of the bar, and the rollers of each pair are spaced 70 75 apart longitudinally so there are four bearings for the bar 22.

The bar 20 projects downwardly through the opening 25 in the base 3 and into the upper part 26 of the cylinder 27. The lower 80 end of bar 22 carries a plunger or piston 28 which can be raised far enough above the top of the effective part of the cylinder 27 to expose the openings 29 so that the clay may be introduced into the cylinder 27 under the piston or plunger before the plunger or piston is moved downward to compress the clay and force it into the pipe-forming cylinder 27. One edge of the bar 22 carries 85 rack teeth which are engaged by a pinion 31 on the shaft 32 mounted in bearings 33, 34 and 35 carried by the base 3. The pinion 31 is between the bearings 33 and 34 and there is a gear 36 on the shaft 32 between the bearings 34 and 35. The gear 36 is driven by a pinion 37 on shaft 38 mounted in bearings 39 on base 3. On shaft 38 there is a brake drum 40 adapted to be engaged by a brake band 41 in an appropriate manner similar to ordinary brake 90 band and drum combinations. The brake drum is fast to the shaft 38 and it carries a cone clutch 42 adapted to be engaged by a socket member 43 loose on shaft 38, and having gear teeth 44 meshing with a pinion 45 on the drive shaft of the electric motor 46. The member 43 is normally urged away from the clutch 42 by an ex-

panding spring 47. There is a sleeve 48 extending over the end of the shaft 38, the sleeve 48 also receiving a shaft 49 which may have slight longitudinal movement 5 with respect to the sleeve, but which may be held against rotative movement with respect to the sleeve by the lugs or pins 50. The shaft 49 and the sleeve 48 may be urged toward the member 44 by a screw 51 carrying a pinion 52 engaged by the teeth of the gear segment 53, the segment being operated by a rod 54.

Assuming that the motor is constantly rotating and it is desired to operate the 15 plunger through the medium of the gearing consisting of the pinion 37, gear 36, pinion 31 and rack bar 22, the rod 54 will be swung to turn the piston 52 to cause the screw 51 to force the shaft 49 and sleeve 20 48 toward the clutch member 43—44, to cause the cone 42 to engage in a socket 43. Then the gear will begin to operate. If it is desired to stop the plunger at any point 25 the brake will be applied. The motor 46 is a reversing motor supplied with current in the usual way, and I have therefore, provided a reversing switch 55 in a circuit consisting of the conductors 56 and 57 so that the gear may be operated to force the 30 plunger downwardly or to retract it upwardly. The bottom of the cylinder 27 is provided with the usual dies 58 and 59 to form the collar on the end of the pipe, this being an old construction, however, so a detailed discussion of its operating is deemed 35 unnecessary.

The adjustment of the rollers 20 is an important feature of my invention because when they are properly adjusted the plunger 40 bar will be held rigid enough between the four rollers to insure a correct rectilinear motion, and yet have enough flexibility to prevent binding of the parts.

It will be apparent that the gear drive 45 will afford a positive power stroke to the plunger bar, so that the pressure against the clay will be uniform throughout the entire stroke of the plunger, which cannot occur where an expansible and contractible 50 fluid medium is used for actuating the plunger.

What I claim and desire to secure by Letters-Patent is:

55 1. A clay pipe forming press comprising a pipe-forming cylinder having means whereby clay may be introduced into the cylinder, a plunger for forcing the clay through the cylinder, a rack bar on the plunger, having grooves in its respective edges, sets of rollers at opposite edges of the rack bar, the rollers of each set having flanges engaging the edge grooves, and means for actuating the rack bar.

60 2. A clay pipe forming press comprising 65 a pipe-forming cylinder having means

whereby clay may be introduced into the cylinder, a plunger for forcing the clay through the cylinder, a rack bar on the plunger, having grooves in its respective edges, sets of rollers at opposite edges of the rack 70 bar, the rollers of each set having flanges engaging the edge grooves, and means for actuating the rack bar, said means comprising a pinion, a shaft on which the pinion is rigidly mounted, a gear rigid on said shaft, a second shaft, a pinion on the second shaft in mesh with the gear, a drive shaft and means for connecting and disconnecting the drive shaft to the second mentioned shaft. 75

3. A clay pipe forming press comprising 80 a pipe-forming cylinder, a plunger movable in the cylinder to force the clay through the cylinder, and operating mechanism comprising two substantially rectangular and vertically disposed brackets, having bearings at their respective corners, horizontal shafts in the bearings of the respective brackets, rollers mounted on the shafts having peripheral flanges, a rack bar rigid with the plunger, having longitudinally disposed edge grooves receiving the flanges on the rollers to guide the rack bar, and means for actuating the rack bar. 85

4. A clay pipe forming press comprising 90 a cylinder having means for shaping clay into pipe, a plunger in the cylinder for forcing the clay therethrough, and means for operating the plunger, comprising two parallel substantially rectangular brackets, having bearings in their respective corners, shafts in complementary bearings in the brackets, rollers carried by shafts having peripheral flanges, a rack bar connected to the plunger, having longitudinal grooves receiving the 95 flanges on the rollers, and means for actuating the rack bar. 100

5. A clay pipe forming press comprising 105 a cylinder having means for shaping clay into pipe, a plunger in the cylinder for forcing the clay therethrough, and means for operating the plunger, comprising two parallel substantially rectangular brackets having bearings in their respective corners, shafts in complementary bearings in the brackets, rollers carried by the shafts having peripheral flanges, a rack bar connected to the plunger, having longitudinal grooves receiving the flanges on the rollers, and reversible means for actuating the rack bar. 110

6. A clay pipe forming machine comprising 115 a pipe-forming cylinder, a plunger for forcing the clay through the cylinder, a rack bar connected to the plunger, a pair of substantially rectangular brackets in spaced relation on either side of the rack bar, adjustable bearings in slots in the corners of the brackets, shafts in the bearings, rollers carried by the shafts, having peripheral flanges engaged in grooves in the rack bar, 120 and means for actuating the rack bar. 125

130

7. A clay pipe forming machine comprising a pipe-forming cylinder, a plunger for forcing the clay through the cylinder, a rack bar connected to the plunger, a pair of substantially rectangular brackets in spaced relation on either side of the rack bar, adjustable bearings in slots in the corners of the brackets, shafts in the bearings, rollers carried by the shafts, having peripheral

flanges engaged in grooves in the rack bar, and means for actuating the rack bar, said means comprising a train of gearing including a driven shaft, a drive shaft, and a clutch mechanism between the drive shaft and the driven shaft. 10

In testimony whereof I affix my signature.

SAMUEL I. FLOURNOY.
